PATENTED JAN. 14, 1908.

J. MITCHELL.

SHOE LINING, BACKSTAY, AND COUNTER.

APPLICATION FILED OCT. 29, 1906.

UNITED STATES PATENT OFFICE.

JACOB MITCHELL, OF DETROIT, MICHIGAN, ASSIGNOR TO MITCHELL SHOE-LINING COMPANY, OF ROYAL OAK, MICHIGAN.

SHOE-LINING, BACKSTAY, AND COUNTER.

No. 876,473.

Specification of Letters Patent.

Patented Jan. 14, 1908.

Application filed October 29, 1906. Serial No. 341,019.

To all whom it may concern:

Be it known that I, JACOB MITCHELL, a citizen of the United States, residing at Detroit, in the county of Wayne and State of Michigan, have invented a new and useful Combination of Shoe-Lining, Backstay, and Counter, of which the following is a specification.

My invention relates to shoes, and more particularly to a combination of lining, back stay and counter, and the object is to provide a construction by means of which the manufacture of shoes may be materially facilitated and the completed shoe strengthened and rendered more comfortable for the wearer.

The invention consists in the particular combination of lining, back stay and counter described in the following specification and set forth in the appended claim.

In the accompanying drawings: Figure 1 is a view of the back stay flattened out; Fig. 2 is a view of the same folded and in readiness to be attached to the counter; Fig. 3 shows the back stay and counter assembled; Fig. 4 shows the next stage of manufacture, with one half of the back stay secured to the lining; Fig. 5 shows the completed article, the back stay being bent over the top of the lining; and Fig. 6 shows an assembled back stay and counter, the latter being padded.

Referring to these views, it will be seen that the back stay C, which may be of cloth, is formed from a narrow elongated blank, as illustrated in Fig. 1. A reinforce strip E may be placed along one end portion of the stay, after which the marginal regions of this half of the stay are bent over upon the reinforcement, as shown in Fig. 2. The next step is to secure the counter D to the broader half of the stay, as shown in Fig. 3, after which the other half of the stay is stitched to one side of the lining along the median or heel line thereof, as shown in Fig. 4. The counter-bearing half of the stay is now bent over upon the other side of the lining, with

the counter between the stay and lining, and stay and counter are secured to the lining, as shown in Fig. 5.

At A in Fig. 6 is indicated how the counter 50 may be padded, to render the heel of the shoe more comfortable to the wearer, or to provide for the absorption of moisture.

The great advantage of the construction shown in Fig. 5 is that the lining is effectually supported and reinforced before the quarters and vamp are attached, thus rendering easier the handling of the lining during the completion of the shoe. This reinforcement of the lining is effected, it will be seen, 60 by the association of the back stay with both sides of the lining and by the rigidity which is afforded by the counter inserted between the lining and stay. It will be obvious that the construction also materially strengthens 65 the completed shoe.

The simplicity of the construction will be apparent, as also the ease with which the parts may be manufactured and assembled. The back stay is in the form of a simple 70 elongated strip and is readily secured to both the counter and lining by merely placing it over these members and stitching. This smooth stay secured over the median line of the lining and over the central portion of the 75 counter insures that the heel of the wearer will not become rubbed and chafed.

What is claimed as new is:

In shoes, the combination of a lining, a back stay in the form of a narrow elongated 80 strip folded centrally over the top of the lining and having its halves secured to the opposite sides of the lining along the median line thereof, and a counter disposed between the base of the lining and the lower portion of one 85 of the strip-like halves of the stay and secured to both the lining and stay.

JACOB MITCHELL.
